Primary Examiner — George J Ulsh*Assistant Examiner* — Gregory G Mclemore(74) *Attorney, Agent, or Firm* — JEEN IP LAW, LLC(57) **CLAIM**

The ornamental design for a toy flower making set, as shown and described.

DESCRIPTION

FIG. 1 is a front, left and top perspective view of the first part of a toy flower making set, showing my new design; FIG. 2 is a rear, right and bottom perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, left and top perspective view of the second part of the toy flower making set;

FIG. 10 is a rear, right and bottom perspective view thereof;

FIG. 11 is a front view thereof;

FIG. 12 is a rear view thereof;

FIG. 13 is a left side view thereof;

FIG. 14 is a right side view thereof;

FIG. 15 is a top plan view thereof;

FIG. 16 is a bottom plan view thereof; and,

FIG. 17 is a perspective view of the two parts assembled together of the toy flower making set.

The broken lines shown in the drawings illustrate portions of the toy flower making set that form no part of the claimed design.
